SUPPORT

Robert L. Mann, Oak Park, Ill.

Application November 7, 1947, Serial No. 784,658

5 Claims. (Cl. 248—102)

1

My invention relates to supports, and includes among its objects and advantages a support of the type used to hold infant's milk bottles, which is cheap and durable and affords improved manipulative advantages to the infant.

In the accompanying drawing,

Figure 1 is a perspective of the complete device in place on a crib;

Figure 2 is a section on line 2—2 of Figure 3;

Figure 3 is a section on line 3—3 of Figure 2;

Figure 4 is a section on line 4—4 of Figure 2;

Figure 5 is a section on line 5—5 of Figure 3; and

Figure 6 is a side elevation, partly in section, of a modified construction.

In the embodiment of the invention selected for illustration, the support includes hook means operating under tension for engaging the side members of the crib; receiving means for holding the bottle itself; and a connection between the receiving means and the hook means whereby the hook means supports the receiving means subject to convenient longitudinal adjustment by the user.

The hook means illustrated in Figures 1 through 5 inclusive, includes two slightly flexible duplicate tension rods 10 and 12. Each rod has its outer end bent to form a hook 14 which is covered with a rubber sleeve 16 to avoid marring the furniture. As clearly indicated in Figure 1, the hooks may be hooked over the side rails 18 of a crib, or any other structural member that happens to be conveniently located. For instance, if the side rails 18 happen to be too high, the hooks can be engaged with the pilasters 20, either with or without a bit of string to keep the hooks from sliding down.

The tension means includes the compression spring 22 encircling the overlapping inner ends of the rods 10 and 12. The rod 10 passes through the spring from right to left, and its end is turned laterally out at 24 and then into an arcuate portion 26 lying in a plane perpendicular to the rod. The arcuate portion provides a firm abutment for the washer 28 against which the spring 22 presses. The left hand rod 12 passes through the spring from left to right and has a duplicate arcuate portion 26 and abutment washer 28. It will be apparent that pulling the hooks 14 apart to engage them with the crib will compress the spring 22 so that the hooks will be resiliently held against disengagement. And because the rods 10 and 12 are slightly flexible, the entire tension connection can sag down a little in the middle, which is desirable.

2

The receiver illustrated in Figures 1 to 5 inclusive includes a spring steel pillar 30 with a large band 32 spotwelded to it near the top and a small adjustable band 34 at the extreme lower end. The lower end of the pillar 30 is bent back up as indicated at 36, and the lower band may be entered in the bight thus formed, and welded or soldered in place. The band 34 is of relatively flexible metal, and its outer ends 38 overlap. Thus the user can readily bend it to define an opening materially larger than that illustrated in Figure 4, or materially smaller, so that a fairly accurate fit can be obtained with the necks of the bottles 40. At its upper end the pillar 30 is bent to define a resilient downwardly opening hook 42.

The connection between the receiver and the tension means is a cylindrical tube 44 housing the spring 22, the washers 28 and the arcuate wire ends 26. It has a closure 46 at both ends to function as an abutment limiting the expansion of the spring 22 when the device is not suspended under tension. The cylindrical exterior of the rod 44 can receive the resilient hook 42 at any point throughout its length.

When in use as in Figure 1, the spring 22 is materially compressed compared with its completely expanded condition in Figure 3. This compression will move the washers 28 toward each other and leave a clearance inside the tube. This clearance permits the tube to slide axially to and fro with respect to the tension connections. Thus the caretaker can set the tension means and tube 44 up on the crib and then hook the receiver and bottle onto the tube 44 in position directly over the infant. If, during feeding, the infant happens to loose hold of the bottle, the tube 44 will swing pivotally about its own axis, but the movement of the bottle will be all in one plane and sufficiently restricted so that even a very small child can nearly always find the bottle again and continue feeding. Furthermore, if the infant happens to roll from side to side a little, all the infant need do is hang onto the bottle and the tube 44 can slide axially for a considerable distance to accommodate the change of position of the infant.

In the embodiment of Figure 6 the receiver may be identical with that in Figure 1, and the tube 48 differs from tube 44 only in having smaller openings in its end closures. The overlapping rods 10 and 12 are replaced by shorter rods 50 and 52, each flexibly connected at 54 to an extension 56 terminating in a rubber-covered hook 58. Tension is provided by a tension spring 60 of

undistorted length much less than the length of the tube 48, which tension spring is connected to the proximate ends of the rods 50 and 52.

Without further elaboration others may readily adapt the invention for use under various conditions of service by employing one or more of the novel features involved, or equivalents thereof. As at present advised with respect to the apparent scope of my invention, I desire to claim the following subject matter:

1. In a support of the class described, in combination: a resilient suspension adapted to span a space between two fixed structures under tension; a receiver shaped to receive an inverted bottle; and a connection between said suspension and receiver for supporting said receiver on said suspension with limited sliding movement in a longitudinal direction along said suspension; said suspension including a central spring to maintain the tension of said suspension; said connection being a tube housing said spring and of greater length than said spring when loaded; said spring being a compression spring, in combination with tension rods extending past each other through said spring and projecting beyond said spring in opposite directions.

2. A support according to claim 1 in which which each tension rod is connected at one end to the adjacent end of said spring and at the other end projects out beyond the end of said tube for attachment to said fixed structure.

3. In a support of the class described, in combination: a resilient suspension adapted to span a space between two fixed structures under tension; a receiver shaped to receive an inverted bottle; and a connection between said suspension and receiver for supporting said receiver on said suspension with limited sliding movement in a longitudinal direction along said suspension; said suspension including a central spring to maintain the tension of said suspension; said connection being a tube housing said spring and of greater length than said spring when loaded; said receiver including detachable means at its upper

end comprising a resilient downwardly open hook for affixing said receiver to said connection in any one of a plurality of longitudinally spaced positions.

4. In a support of the class described, in combination: a resilient suspension adapted to span between two fixed structures under tension; a receiver shaped to receive an inverted bottle; a connection between said suspension and said receiver; said suspension comprising two tension members adapted to be secured to said structures and a spring secured to and joining said members; said connection comprising a tube housing said spring and of a length substantially in excess of the loaded length of said spring so that said tube has a limited sliding movement in a longitudinal direction along said suspension.

5. A bottle support comprising, in combination: a resilient suspension including two tension members and a centrally located spring joining said members adapted to span between two fixed structures under tension; a receiver for receiving an inverted bottle; a connection between said suspension and said receiver; said connection comprising a tube housing said spring and of a length in excess of that of the spring when loaded; said tube being adapted to slide longitudinally of said suspension for properly positioning said receiver; said receiver comprising a pillar supporting two spaced bands, the lower of the said bands being circumferentially adjustable; and the pillar being bent at its upper end to form a downwardly opening hook for affixing said receiver to said tube.
